MARIUS KLEBER MAKARÉWIEZ, OF COURBEVOIE-SEINE, FRANCE.

APPARATUS FOR BORING THE CONNECTING RODS AND BEARINGS OF INTERNAL-COMBUSTION ENGINES.

Application filed December 6, 1922. Serial No. 605,220.

To all whom it may concern:

Be it known that I, MARIUS KLEBER MAKARÉWIEZ, a citizen of the French Republic, of 65 Rue de la Sabliere, Courbevoie, Seine, France, have invented Apparatus for Boring the Connecting Rods and Bearings of Internal-Combustion Engines, of which the following is a full, clear, and exact description.

10 The invention relates to an apparatus adapted to be used for the quick and adequate boring of the cross-heads or big ends of connecting-rods for internal-combustion engines, as well as for the boring of their 15 bearings.

This apparatus essentially comprises a bed upon which the work is placed and secured after adjustment, and this so that a tool-holding shaft passes through the eye of 20 the connecting-rod crosshead, which a supporting stem introduced into the lower eye of the connecting-rod holds the same on the bed.

The apparatus also comprises a differential gear which allows to cause the tool-holding shaft to advance slowly in a rectilinear direction while the same rotates quickly upon itself. This gear allows furthermore, through a clutch and suitable 30 couplings, to carry quickly the shaft towards the work and to return same also quickly to its original position while it continues to rotate at the same speed.

This apparatus answers perfectly well to 35 its purpose by the fact that it enables any repairing workman to quickly and adequately bore the connecting-rods and bearings without it being necessary to make use of a costly lathe.

40 This invention will be hereinafter described with reference to the accompanying drawings in which:

Fig. 1 shows in cross-vertical section one form of construction of the apparatus.

45 Fig. 2 is a plan view of same, and

Fig. 3 is a side view seen from the right-hand side of Fig. 1.

Fig. 4 is a rear view of the apparatus.

50 Figs. 5 and 6 show a subsidiary tool used when boring bearings.

Fig. 7 shows in side-elevation a second mode of construction of this apparatus.

Fig. 8 is a corresponding plan view.

Fig. 9 is an end-view from the left of Figs. 7 and 8.

55 Fig. 10 is a vertical section taken on the center line of the shaft *b* and corresponding to Fig. 9 of the drawings.

Fig. 11 shows, in side-view, a nut-collar or clamping-collar applied upon the shaft 60 of this apparatus in a position corresponding to Figs. 9 and 10 of the drawings.

Fig. 12 shows the same clamping collar in a position at right angle to the shaft upon 65 which it is mounted.

As shown in the drawings, the apparatus, in the form of construction shown in Figures 1 to 4, comprises a frame or bed *a* of a rectangular shape, provided at one end, on the sides, with the bearings *a*¹ through 70 which passes the shaft *b* carrying the tool *c*, while the bed *a* is adapted to support the piece of work.

The shaft *a* is provided with screw threads 75 upon a part of its length and is provided with a driving fly-wheel *b*¹. The projection of the tool *c* from the shaft is regulated and adjusted by means of a screw driving device *c*¹ the head of which carries a setting or adjusting graduation or scale.

Upon the threaded part of the shaft *b* is mounted a nut *d* meshing with the screw-threads of this shaft. This nut is made of two parts which form a collar, and are hinged or pivoted to an axle *d*¹ and provided with a closing or locking device on the side opposite to the axle.

The shaft *b* is surrounded by a smooth sleeve *e* and these two parts are connected together by a key *b*² carried by the shaft.

Upon one end of the sleeve *e* is fixed a pinion *f* adapted to mesh another pinion *g* connected with a shaft *h* passing through the bearing.

To the opposite end of this shaft *h* is 95 keyed another pinion *i* which transmits the motion to a pinion *j* which is loose upon the sleeve *e* but which is connected with the nut *d* by means of the axle *d*¹ upon which the two parts of this nut are pivoted.

This reducing gear operating the nut can vary as to the ratio between the pinions.

By opening the nut d , the shaft b may be caused to slide in its sleeve e , to the right.

On one side of the frame a is a right-angle cheek or jaw a^2 carrying at the top a graduation or scale a^3 .

This jaw is provided with a straight slot a^4 in which can slide a bolt h supporting two conical rings l l^1 turned in an opposite direction the one to the other.

The bed a also carries two opposing clamping screws m .

The foot or small end of the connecting-rod which is to be bored being mounted on the cones, the pointer of the cone l^1 is brought opposite the slot or graduation a^3 corresponding to the distance apart between two axles which is to be given to the connecting-rod; this rod is then secured by means of the clamping screws m .

The shaft b is then partly removed from the bed and introduced into the eye of the crosshead of the connecting-rod; the projection of the tool c is adjusted by means of the screw c^1 , the tool being placed close to the connecting-rod, the nut d is closed upon the threaded part of the shaft b , and then by turning the flywheel b^1 with the hand 30 the automatic advance of the tool c is caused. The nut d is thus carried along, but at a speed which is less than that of the tool-holding shaft, according to a suitable ratio between the pinions.

35 This apparatus can also be driven mechanically.

For the boring of bearings, the cones l l^1 are removed and also the clamp screws m , and the subsidiary tool n , Figures 5 and 6, 40 is fixed to the bed a by mounting the same in the slot a^4 of this bed. The bearings which are to be bored are placed in the parts p p^1 , which are clamped by means of bolts q and the centering as to the height is obtained and maintained by using the pointer r , Figure 6, and the scale a^3 Fig. 2.

In the second form of construction shewn in Figures 7 to 11, the apparatus also comprises a frame or bed a provided at one end, 50 on the sides, with the bearings a^1 and a bracket a^5 through which the tool-carrying shaft b passes.

The shaft b as before pointed out is threaded upon a part of its length and is 55 provided with a rectilinear groove b^3 extending from one end to the other, and, it is mounted loosely in sleeve e . An annular head s , provided with clutch teeth s^1 extending towards the left, is slidably mounted upon the shaft b , while a lug s^2 carried by this head and entering the said groove b^3 prevents the said head from rotating.

60 The sleeve e carries a clutch pulley t which is loose thereon and said pulley is provided 65 on its opposite faces with clutch teeth t^1 t^2 .

The head s and the pulley t can also be shifted in and out of gear by virtue of their particular mounting, by means of two forks u , u^1 the arms of which are engaged into grooves formed in these respective parts. 70 The fork u is secured fast to the driving shaft v of the clutch, while the fork u^1 is loosely mounted on the same shaft v between two stops v^1 v^2 fixed upon the said shaft and provides for dead or lost motion. 75

A spring latch x which is adapted for engagement in either one of two notches or grooves formed in the socket of the fork u^1 of the pulley t , serves to maintain this fork and this pulley either in or out of gear, as it will be explained later on. 80

A handle y pivotally mounted at y^1 and suitably jointed at y^2 to the axle v serves to operate the said forks u u^1 .

On the side opposite to the head s , the pulley t is provided with teeth t^2 in front of gearing teeth f^1 carried by a small pinion f loose on the sleeve e .

The small pinion f is in mesh with the large pinion g keyed upon shaft h said shaft being provided on the other side of the bearing, with the small pinion i meshing with the large pinion j loosely mounted upon the sleeve e . 90

This pinion j is connected with the collar d , made of two parts and forming a nut threaded upon the shaft b . The two branches or parts of this collar are hinged together upon the axle d^1 while the same branches or parts are crossed on the side opposite to the axle and at right angle to the latter by a threaded bolt d^2 having on one end a nut d^3 and provided at the other or head end with a lever clamping cam d^4 . A spring d^5 interposed between the two parts of this collar causes the latter to separate when the cam d^4 is in the loosened position. 100

The shaft b carries the tool c held by the screw-device c^1 whose graduated head permits adjusting the projection of the nose of this tool into the piece of work. 110

A support comprising the threaded pin or bolt k carries cones l , l^1 the one of which l , is movable and acts as a nut. This support can slide in the straight slot a^4 provided in the cheek or jaw a^2 of the bed a , in front of the graduated scale a^3 . 115

The two side clamp screws m clamp between them, after adjustment, the piece of work. Finally a clamping screw z is employed to hold the piece of work from underneath and serves to adjust the height of the latter.

The tool c is first brought rapidly towards the work, but as soon as this tool is about to come into contact with the work, its advance or motion is slackened while the pulley t still turns at the same rate. This 125 automatic differential advance of the tool- 130

holding shaft b is obtained through the medium of the gears f g i j , as above stated.

When the device is at rest, the pulley t is loose, but when the handle y is moved in the direction indicated by the arrow, Figure 9, the fork u is shifted to the left carrying with its head s , which movement brings the teeth s' of the head s in mesh with the teeth t^1 of the pulley t .

10 The head s now being in gear with the pulley t and this head being connected with the screw tool-holding shaft b the latter rotates.

15 The collar being unable to move in the rectilinear direction, the shaft b , driven directly at this moment by the pulley t , the head s and the nut j move forwards to the left at as fast speed.

If now the handle y is pushed home in the same direction, Figure 9, the stop v^2 pushes the fork u^1 towards the left, so that this fork shifts at its turn the pulley t , the teeth t^2 of which come in gear or in mesh with the teeth f^1 of the small pinion f .

25 The small pinion f meshes with the large pinion g connected through its shaft h with the small pinion i meshing with the large pinion j .

The pinion j being connected with the nut d , the latter rotates at a reduced rate and as it can only rotate, it causes the shaft b to advance at a relatively slow speed as well as the tool c carried by the latter, while the rate of revolution remains the same.

At the last shifting of the clutch, the spring latch x has dropped into the notch u^2 and maintains the corresponding fork u^1 and the pulley t in the working position.

40 The reverse of the above operation will put the mechanism out of gear.

During this time, and on account of the time lost according to the position of the stop v^1 , the pulley t remains in gear, so that 45 the pinions f g i j continue to turn, but the shaft b no longer rotates because the driv-

ing head s is out of gear; hence, the nut d causes the screw tool-holding shaft b to return at a great speed.

In pushing home the handle y , the stop v^1 acts upon the fork u^1 of the pulley t , which has the effect of bringing back the spring latch u^2 to the first notch or groove of the clutch.

The forms, details, accessories, materials and sizes of this apparatus can of course vary without departing in any way from the principle of the invention.

I claim—

An apparatus of the character specified, comprising a platform, means for fixing the work thereon, a head perpendicular and rigidly mounted on said platform, bearings carried by said head, a sectional nut supported by one of said bearings, a tool holding shaft mounted in said bearings, said shaft having a threaded part engageable in said nut and supported by one of the bearings, a loose pulley mounted on said shaft, means for communicating a rotating movement to said shaft, means for transmitting rotary movement to said nut and in the same direction as said shaft, and at a lower speed, whereby to create a differential movement and giving to said shaft reduced displacing movement, means for putting the nut into and out of gear with the loose pulley, said means comprising a fork adapted to engage the nut, and a second fork adapted to engage the loose pulley, a shaft carrying said forks, the first named fork being fixed on to said shaft, the second fork loosely mounted on the said shaft between a pair of stops fixed thereon and provided with a pair of notches, whereby the second named fork and the pulley may be put out of gear, and a hand lever pivotally mounted on said platform and articulated at its lower end to the end of the last named shaft whereby to operate the said forks.

MARIUS KLEBER MAKAREWIEZ.
